FOLDED PAPERBOARD OPTICAL VIEWER OR THE LIKE

Charles R. Gretz, Springfield, Mo., assignor to
CTV Products, Inc., Springfield, Mo.

Filed Nov. 9, 1972, Ser. No. 305,160

Term of patent 14 years

Int. Cl. D16—06

U.S. Cl. D57—1 E

FIG. 1

FIG. 6

FIG. 2

FIG. 3

FIG. 4

FIG. 5

FIG. 1 is a top plan view of a folded paperboard optical viewer showing my new design;

FIG. 2 is a front elevational view thereof;

FIG. 3 is a bottom view taken in the direction of line 3—3 of FIG. 2;

FIG. 4 is a rear elevational view thereof;

FIG. 5 is an end elevational view thereof; and

FIG. 6 is a sectional view, on an enlarged scale, taken along line 6—6 of FIG. 2.

I claim:

The ornamental design for a folded paperboard optical viewer or the like, substantially as shown and described.
